(57) CLAIM

The ornamental design for a surface configuration of a vehicle spoiler, as shown and described.

DESCRIPTION

FIG. 1 is a top perspective view of a first embodiment of a surface configuration of a vehicle spoiler according to my novel design;

FIG. 2 is a right side perspective view of the first embodiment of the surface configuration of a vehicle spoiler according to my novel design, the left side perspective view being mirror symmetrical;

FIG. 3 is a right side view of the first embodiment of the surface configuration of a vehicle spoiler according to my novel design, the left side view being mirror symmetrical;

FIG. 4 is a top perspective view of a second embodiment of the surface configuration of a vehicle spoiler according to my novel design;

FIG. 5 is a right side perspective view of the second embodiment of the surface configuration of a vehicle spoiler according to my novel design, the left side perspective view being mirror symmetrical; and,

FIG. 6 is a right side view of the second embodiment of the surface configuration of a vehicle spoiler according to my novel design, the left side view being mirror symmetrical. The broken lines are for illustrative purposes only and form no part of the claimed design.
